United States Patent Office

Des. 188,052
Patented May 31, 1960

188,052

TRANSFORMER VALVE

Charles A. Davis, % The Ohio Brass Co., Mansfield, Ohio

Filed May 26, 1959, Ser. No. 56,065

Term of patent 14 years

(Cl. D26—15)

FIG. 2

FIG. 1

FIG. 3

FIG. 4

FIG. 5

FIG. 6

Fig. 1 is a front elevational view of a transformer valve, showing my new design;

Fig. 2 is a top plan view;

Fig. 3 is an end elevational view;

Fig. 4 is a bottom plan view;

Fig. 5 is a rear elevational view; and

Fig. 6 is an opposite end elevational view thereof.

I claim:

The ornamental design for a transformer valve, as shown.
